(57) **CLAIM**

The ornamental design for a nipple for children's bottle as shown and described.

DESCRIPTION

FIG. 1 is a front upper perspective view of a nipple for children's bottle, showing our new design;

FIG. 2 is a front view thereof;

FIG. 3 is a rear view thereof;

FIG. 4 is a right-side view thereof;

FIG. 5 is a top view thereof;

FIG. 6 is a bottom view thereof; and,

FIG. 7 is a cross-sectional elevation view of the nipple for children's bottle of FIG. 1, taken in the direction of line 7-7 of FIG. 5.

In the drawings, the equal-length broken lines depict portions of the nipple for children's bottle that form no part of the claimed design. The dash-dot-dash broken lines define the boundaries of the claim. All broken lines form no part of the claim.
